UNITED STATES PATENT OFFICE.

WILLIAM E. SWINDELL, OF MOBERLY, MISSOURI.

ATTACHMENT FOR CUTTING FELLIES OR THE LIKE.

SPECIFICATION forming part of Letters Patent No. 707,179, dated August 19, 1902.

Application filed May 16, 1902. Serial No. 107,632. (No model.)

To all whom it may concern:

Be it known that I, WILLIAM E. SWINDELL, a citizen of the United States, residing at Moberly, in the county of Randolph and State 5 of Missouri, have invented new and useful Improvements in Attachments for Cutting Fellies or the Like, of which the following is a specification.

My invention relates to an attachment for 10 band-saw or jig-saw tables for guiding stock to be cut into fellies, half-rims, pulley-sections, cants, and other pieces which have to be cut into segmental forms.

I will proceed to describe my invention with 15 reference to the accompanying drawings, in which—

Figure 1 is a plan view of an attachment embodying my invention, the table and a certain plate being partly broken away. Fig. 2 20 is a vertical section of the attachment and the table, taken on line *a b* of Fig. 1, showing a portion of the saw. Fig. 3 is a transverse section of the pivot-arm and a part of the carrier, showing the pivot-bolt. Fig. 4 is a 25 top plan view of the pivot-arm detached from the table. Fig. 5 is a diagram illustrating the cuts required for a felly or the like. Fig. 6 is a bottom plan view of the table reduced in size, showing the stops for the carrier. Fig. 30 7 is an enlarged isometrical view of one of said stops.

1 designates a portion of a saw-table, and 3 is the portion of the saw passing through the table.

35 My attachment comprises a slotted arm 4 and a carrier-frame 5 21 12, mounted pivotally on the arm, as presently described. The arm 4 is secured to the bottom of the table with bolts 6. The outer half of the arm has 40 extra thickness, so that its upper face comes flush with the top of the table, as shown. A longitudinal slot 7 is cut in the projecting portion of the arm 4 to receive a pivot-bolt 8. A washer 9 is secured permanently on said 45 pivot-bolt and rests on the arm 4, thereby supporting said bolt. Below said arm said bolt is provided with a wing-nut 14, by tightening which bolt 8 may be secured at any point along the slot 7.

50 The carrier-frame or carrier 5 21 12 is constructed as follows: Radial arms 5 12 13 have

their converging ends secured to a rectangular casting 15. One of the outer arms 5 is bent at 16, and its outer end is secured to an arc-piece 17, made preferably of angle-iron. The 55 arms 5 12 13 are also of angle-iron. The divergent ends of the inner arms are secured to an arc-piece 18 and are further connected by arc-shaped stiffeners 19.

Secured to the outer arc-piece 17 by rivets 60 or screws are a pair of bent guides 21, which are separated from each other by thick washers or collars 22. Two guides 23 are held upon the bent guides 21 by bolts 24, passing between the latter. Guides 23 are slotted, as shown, 65 to permit of longitudinal adjustment thereof to determine the width of the fellies, &c.

Connected to the outer end of arm 12 by a hinge 26 is a gate 27, made of a piece of angle-iron. The purpose of this gate is to permit 70 the saw 3 to be inclosed within the gate 27, arc-pieces 17 and 18, and arm 5. A drop-latch 28 is pivoted on the gate 27 and holds the gate closed by entering a notch in the upper edge of arc-piece 17. Any preferred latch for the 75 gate may be employed.

For supporting the pieces of stock to be cut a wooden plate 29 is laid upon the flanges of the arc-pieces 17 18 and of arm 5. A handle-knob 31 is secured to the arm 5 for actuating the carrier 5 21 12 when cutting stock, and the plate 29 is cutaway, as shown, around said knob, so that it may easily be removed from the carrier and another plate substituted for it, as a plurality of plates, like 29, 80 85 are employed in making cuts of different curvatures. In each plate is a curved saw-cut 32, made by the saw in the manner presently described. Plates 29 all have the same contour and thickness, and the only difference 90 between them is in the curvature of their respective saw-cuts 32.

In the bottom of the aforesaid rectangular casting 15 is a longitudinal slot 33, through which projects the upper end of the pivot-bolt 8 when the carrier is in operative position. Secured to one side of casting 15 is a rack 34, the teeth of which are sharp and substantially rectangular and are directed toward the slot 33.

35 is a triangular block, the apex of which is adapted to fit between any two teeth of the

rack 34. In block 35 is a vertical perforation adapted to fit, but not tightly, over the upper end of the pivot-bolt 8.

Secured beneath the corners of the table 5 are two stops 36 for limiting the movement of the carrier, and hence the length of the cut made by the saw. Each said stop has an upwardly-projecting portion, as shown in Fig. 7, which is struck by the carrier at the beginning or end of a full-length cutting stroke. In each stop is a slot 37, through which and the table passes a bolt 38. Thus the stops are adjustable for cuts of different lengths. Said stops may be longer proportionately than 10 15 shown in the drawings.

The operation of the attachment is as follows: The arm 4 is secured to the table with bolts 6. The radius of curvature of the first cut to be made is determined and the pivot-bolt 8 is set with its center at that distance 20 from the saw 3. Wing-nut 14 is tightened up to hold the pivot-bolt immovable. The carrier is laid on the table with the slot 33 of casting 15 over the pivot-bolt 8. The gate 27 25 is opened, and a plate 29, having a saw-cut 32, which will register with the cut to be made in the stock, is placed in the carrier. The carrier is swung around to the left to permit the saw to enter the cut 32, and the gate 30 27 is closed and latched. The triangular block 35 is slipped on the upper end of the pivot-bolt 8, and the point of the block will fit between two teeth of the rack 34 as the cut 32 in plate 29 has previously been made 35 by using the carrier pivoted by means of this block. The carrier is now provided with a fixed center of rotation or oscillation. The carrier is turned till the saw is at one end of the cut 32 and the piece of stock to be cut is 40 placed against the inner ends of the guides 23 and held there with one hand, while the carrier is turned by the other hand on knob 31, either pushing or pulling the stock against the saw until the cut is made. The first cut 45 is preferably for the outer curve of the felly, cant, or whatever the piece may be intended for. The small piece cut away by the saw is removed from the carrier and the curved edge of the stock is placed against the guides 50 23 and held there while the inner cut is made, said guides having previously been set at a distance from the saw-cut 32 equal to the desired width of the finished piece. After this second cut the piece would appear as shown 55 in full lines in Fig. 5. The second (inner) cut being of the same radius as that of the first (outer) cut, and the piece would be thicker in the middle than at its ends, as shown. So a finishing cut must be made parallel to the 60 outer cut. To make the finishing cut correctly, the block 35 is removed from the pivot-bolt 8 and the pivot-bolt is moved in toward

the saw until its distance from the saw equals the radius of the desired finishing cut. This must be done without moving the carrier. 65 Plate 29 is removed from the carrier and another plate having a saw-cut of shorter radius is placed in its stead. Then the block 35 is replaced on the pivot-bolt and pushed down to engage the teeth of the rack 34. 70 Then the piece being held against the guides 23 the finishing cut is made, which takes out a thin crescent-shaped piece from the inner side and leaves the felly, cant, or other piece the correct shape. In cutting a number of 75 fellies or the like the first and second cuts of all of them are made before any of the finishing cuts are made. The purpose of this is to save the time which would be required for adjusting the pivot-bolt and changing 80 plates 29 for each piece.

Having now fully described my invention, what I claim as new, and desire to secure by Letters Patent of the United States, is—

1. In a device for the purpose set forth, a 85 sector-shaped frame for carrying the stock, a hinged gate mounted at one side of said frame, and a segmental plate, adapted to be carried by said frame, for supporting the stock, the material of said plate being soft enough to be penetrated by the saw; substantially as described.

2. In a device for the purpose set forth, a sector-shaped frame for carrying the stock, a segmental plate, adapted to be carried by 95 said frame, for supporting the stock, the material of said plate being soft enough to be penetrated by the saw, curved guides, forming a curved slot, secured to the curved periphery of said frame, bolts passing through 100 said slots, and guide-pieces 23 held by said bolts against said curved guides; substantially as described.

3. In a device for the purpose set forth, the combination with a saw-table of a longitudinally-slotted arm adapted to be secured to the table, a sector-shaped frame for carrying the stock, a slotted casting secured to the converging sides of said frame, a pivot-bolt depending through the slot in said arm and having a portion projecting upwardly through the slot in said casting, a rack having inwardly-pointed teeth secured to one side of said casting, and a block having a perforation therein adapted to receive the upper end 105 of said pivot-bolt and a point adapted to enter between any two of said teeth; substantially as described.

In testimony whereof I affix my signature in the presence of two witnesses.

WILLIAM E. SWINDELL.
